UNITED STATES PATENT OFFICE.

OSCAR R. CARLSON, OF CHICAGO, ILLINOIS.

ANCHORING DEVICE

1,317,073.

Specification of Letters Patent. Patented Sept. 23, 1919.

Application filed March 29, 1919. Serial No. 286,068.

To all whom it may concern:

Be it known that I, OSCAR R. CARLSON, a citizen of the United States, residing at Chicago, in the county of Cook and State of Illinois, have invented new and useful Improvements in Anchoring Devices, of which the following is a specification.

This invention relates to anchoring devices for fence posts, telegraph poles, and the like, and has for its object the provision of means whereby a post such as the corner post of a fence may be effectively anchored and braced whereby dislocation of the post will be positively prevented and whereby a strong and substantial structure will be provided.

An important object is the provision of anchoring means of this character in which the various interconnected members are arranged at angles to one another whereby a direct pull upon any portion will be eliminated, thus reducing any possible weakness to the minimum, the structure being adapted for use in many capacities and not being limited in use in connection merely with fences.

A further object is the provision of a structure of this character in which means is provided whereby one of the members may be disconnected from an associated holding member whereby to permit disassembling of the parts.

A further object is the provision of a structure of this character which will be simple and inexpensive in manufacture and installation, highly efficient and durable in use, and a general improvement in the art.

With the above and other objects and advantages in view, the invention consists in the details of construction to be herein-after more fully described and claimed, and illustrated in the accompanying drawings, in which—

Figure 1 is a side elevation showing my structure arranged as one corner of a fence, the earth being shown in section.

Fig. 2 is a sectional view on the line 2—2 of Fig. 1.

Fig. 3 is a sectional view on the line 3—3 of Fig. 1.

Fig. 4 is a detail view of one of the attaching clips.

Fig. 5 is a view similar to Fig. 1 showing the device modified for use in soft earth.

Fig. 6 is a perspective view of an angle member used in this form of the device.

Fig. 7 is a view similar to Fig. 1, showing double bracing means extending in opposite directions.

Fig. 8 is a sectional view through the earth showing my anchoring device adapted for bracing poles and the like.

Fig. 9 is a similar view showing a modification of this form of the device, and

Fig. 10 is a perspective view of an anchor plate used in the form illustrated in Fig. 9.

Referring more particularly to the drawings, the letter A designates the earth and B designates a hole which is dug or bored into the earth.

In adapting my device for use in fence structures, I provide an angle bar 15 which is provided throughout its length with a plurality of holes 16 through which selected ones of which may be passed the line wires 17 of a fence and through other selected ones of which may be passed bolts 18 which extend through attaching plates 19 which are apertured, as shown. The angle bar 15 is intended to be placed, and is shown as being, in inclined position with respect to the surface of the ground A. At its lower end the bar 15 has secured thereto a transversely extending angle bar 20 which is, together with the lower end of the bar 15, buried within the ground.

Disposed within the hole B is a member 21 which may be a cable, wire, or rod, and which is provided at its end within the hole, with a loop or the like 22. The upper end of the member 20 is connected with the uppermost one of the plates 19 by any suitable means. Intermediate its ends the member 20 has formed thereon or secured thereto, an eye 23 to which are connected rods 24 which extend upwardly in inclined directions and which are connected with the other attaching plates 19.

I further make use of an angle bar 25 which is driven into the ground A immediately beneath the bar 15 in an inclined direction and in such a way as to intersect the hole B, this bar 25 engaging within the loop 22 at the lower end of the member 20.

In setting up the structure, the bar 15 is first placed in position with the lower end thereof and the bar 20 buried. The member 20 connected with the upper end of the bar 15 is then placed within the hole B after which the angle bar 25 is driven into the ground until its point, which is sharpened, as shown, enters the hole B. The member

21 is then moved so that the loop 22 thereon will be engaged over the end of the angle bar 25, after which the bar 25 is driven more deeply to extend entirely across and beyond 5 the other side of the hole B. It is of course understood that the rods 24 are connected with the attaching plates 19 at the most suitable time. It will be observed that by virtue of the series of holes 16 the line wires 10 17 of the fence may be disposed at different distances apart by engaging them within selected holes and that the plates 19 may be so adjusted longitudinally of the bar 15 as to exert the proper tension upon the bar.

15 Referring to Figs. 5 and 6, it will be seen that I have provided a slight modification which renders the device very suitable for use in very soft ground, this slight change being necessary in order to effect a more 20 positive anchoring. In this form the member 21, in addition to being provided at its lower end with the loop, as in the previous form, has slidably mounted thereon an L-shaped plate 26 which has its horizontal 25 flange 27 provided with a hole for the passage of the member 21. In setting up this form of the device, the member 21 is engaged over the end of the angle member 25 as in the previous form, after which the 30 plate 26, which is initially held in elevated position, is allowed to slip downwardly along the member 21 until it engages the top edge of the member 25. The member 25 is then driven in more deeply as in the previous 35 form. It is understood, of course, that in both forms, after the structure is set up the hole B is filled with earth or other material, which is tamped down. In this form of the device it will be obvious that there 40 will be no danger of the member 21 slipping upwardly along the bar 25 even though the ground be very soft as the member 21 would carry with it the plate 26 and such would be impossible.

45 Referring to Fig. 7 it will be seen how my structure may be so arranged as to provide additional strength, as for instance at the corner of a fence. Referring to this figure it will be seen that in addition to the member 50 21, and angle member 25, which are identically the same as in the previously described form, I provide a second member 28 which is similar to the member 21 except that the ring member 23 is omitted. This 55 member 28 is auxiliary to the member 21 and is provided at its lower end with a loop 29 through which extends an inclined anchor angle bar 30 which is arranged in offset relation to the member 25. The provision 60 of these two inclined angle members 25 and 30 makes a most secure means for holding down the upper end of the bar 15 so as to very effectually prevent any displacement thereof.

65 In all these forms of the device it will

be seen that the posts constituting a fence may be formed simply as a plurality of bars 15 having the anchoring means associated therewith. The line wires 17 may extend across a plurality of the posts or 70 bars 15, as will be obvious. In forming a corner of a fence the arrangement is preferably that shown in Fig. 7 so as to insure great strength. In constructing a corner a pair of the bars 15 will be used arranged 75 at ninety degrees (90°) apart so that the line wires 17 leading from one of the bars 15 would be at right angles to those leading from the other bar 15. In such an event the rods 24 serve to fill the gap between the members 21 or 28, as the case may be, and the adjacent bar 15.

In adapting my structure for use in bracing telegraph poles and the like, I make use of the expedients disclosed in Figs. 8, 85 9 and 10. As shown in Fig. 8, I make use of an angle member 31 which is the same in cross sectional configuration and other respects, as the member 25 previously described. This member 31 is provided at 90 one end with a hole 32 serving as attaching means for a guy wire or rod 33 and is provided at a point spaced from its pointed end 34 with a transverse hole 35 through which may be passed a pin 36 disposed 95 within the hole B. It will be seen that the pin 36 will prevent the member 31 from being withdrawn from the ground and the anchoring effect will thus be positive. When it is desired to remove the member 100 31 it is merely necessary to first remove the pin 36, after which the member 31 may be pulled out of the ground.

Referring to Figs. 9 and 10, it will be seen that I make use of a plate 37 disposable 105 within the hole B and provided with an opening 38, preferably of the same shape as the cross sectional configuration of the member 39, which is identically the same as the member 31 shown in Fig. 8. In this 110 form the arrangement is identically the same as in Fig. 8 except that the member 39 is passed through the hole 38 in the plate 37 before the pin 40 is inserted. The plate 37 and also the pin 40 have preferably attached thereto wires or other flexible members 41 and 42, respectively, whereby they may be conveniently lowered into the hole B.

From the foregoing description and a 120 study of the drawings it will be apparent that I have thus provided means whereby a post or other object may be effectively and quickly anchored in such a way as to positively prevent dislocation or loosening 125 of any of the parts of a structure to which the device may be applied.

While I have shown and described the preferred embodiment of my invention, it is of course to be understood that I reserve 130

the right to make such changes in the form, construction, and arrangement of parts as will not depart from the spirit of the invention or the scope of the subjoined claims.

5 Having thus described my invention, I claim:—

1. An anchoring device of the character described comprising an inclined bar adapted for connection with the line wires of a fence, a transverse bar carried by the lower end of said bar and embedded within the ground, the ground being provided at a point below the upper end of said first named bar with a hole, a member connected at its upper end with the upper end of said first named bar and having its other end disposed within said hole and provided with an attaching loop, a ring on said member intermediate the ends thereof, a plurality of rods connected with said ring and adjustably connected with said first named bar at spaced intervals, and an angle bar driven

into the ground in intersecting relation to said hole and engaging within said loop.

2. An anchoring device of the character described comprising an inclined angle bar having one end securely embedded within the ground, said angle bar being adapted for connection with the line wires of a fence, the ground having formed therein a hole disposed beneath the upper end of said angle bar, a member connected with the upper end of said bar and having its other end provided with an attaching loop disposed within said hole, rods connected with said member and with different points along the length of said angle bar, an angle bar driven into the ground in intersecting relation to said hole and engaging through said loop, and an L-shaped plate slidable upon said member and adapted to be disposed within said hole. 35 40

In testimony whereof I affix my signature.
OSCAR R. CARLSON.
